RECOVERY OF CYCLO AND METHYLCYCLO-PENTADIENE BY LIQUID VAPOR PHASE CRACKING

Glen P. Hamner, Baton Rouge, La., assignor to Esso Research and Engineering Company, a corporation of Delaware

Application September 25, 1952, Serial No. 311,457

4 Claims. (Cl. 260—666)

This invention relates to a process for separately dedimerizing the high-purity dimers of cyclopentadiene and methylcyclopentadiene from petroleum streams containing a complex mixture of cyclo-alkadiene dimers and codimers.

Highly cracked petroleum fractions, as is well known in the art, contain a variety of cyclodiene compounds—for example, the monomers of C_5 and C_6 cyclopentadienes, their higher homologs, also, the dimers, codimers, higher polymers of these homologous cyclodienes, and interpolymers with other diolefins. The dimer and codimer forms are stable at ordinary atmospheric temperatures, but on being heated to elevated temperatures of the order of 140° C. and higher they start to undergo cracking or depolymerization. The monomeric forms are unstable even at ordinary temperatures and undergo rapid polymerization in the range of 25° — 120° C.

A typical steam cracking operation, which is not part of this invention but is given for background and illustrative purposes only, thus comprises cracking petroleum hydrocarbons boiling in the range of 121° — 371° C. in the vapor phase at 538° C. to 871° C. for a short period of 1 to 5 seconds, preferably in the presence of 50 to 90 mole per cent steam based on the hydrocarbon feed and under a pressure of 1 to 10 atm. The naphtha distillate distilled from the cracked petroleum will be of approximately C_1 — C_{16} range and will contain C_5 and C_6 cyclopentadienes in various forms, monomers, dimers, and codimers, together largely with unsaturated aliphatic hydrocarbons and aromatic hydrocarbons within this range.

The naphtha distillate is treated by distillation, etc., to remove the lower and higher boiling fractions by means known in the art (e. g., see U. S. Patent No. 2,511,936).

This leaves fractions of crude, cracked petroleum naphtha boiling in the approximate range of C_5 (15° C.) to 140° C. and higher, which are then thermally soaked for 4 to 8 hours at temperatures from about 90° — 110° C. This converts any cyclopentadiene and methylcyclopentadiene monomers in the naphtha to dimer and codimer forms. The soaked material is then steam or vacuum stripped to remove C_5 — C_9 components, leaving as residue a concentrate containing from 55 to 82 weight per cent, usually 60—75 weight per cent, of cyclopentadiene plus methylcyclopentadiene present as dimers and codimers and boiling in the range of about 150° — 220° C., 85% or more boiling in the range of about 170° — 220° C. It is this concentrate that preferably represents the feed stock for the present invention. The process is applicable to feed stocks containing as little as 20 weight per cent cyclopentadiene and methylcyclopentadiene as dimers and codimers or as high as 93% on the same basis.

In the past many sequences of operations were attempted in order to recover these cyclodiene fractions economically, but all were dependent on a preliminary step of dedimerizing the cyclopentadiene and methylcyclopentadiene dimers and codimers. Thus conventional vapor phase or liquid phase dedimerization has been uti-

2

lized in order to recover the cyclic diolefin monomer from the dimers. Vapor phase dedimerization at high temperatures, however, results in extensive undesirable coking. Liquid phase dedimerization results in lower conversion and recovery of cyclic monomers.

This invention provides an improved method for dedimerizing and recovering high purity cyclopentadiene and methylcyclopentadiene in separate fractions, if desired, from cracked petroleum streams containing them. The method comprises dedimerizing the cyclopentadiene and methylcyclopentadiene dimers and codimers in the vapor phase while simultaneously passing the vapors countercurrent to a superheated oil in a tower such as a bubble cap type tower. Efficient dedimerization results with a minimum of fouling from coking. The C_5 — C_6 cyclic diene monomers and acyclic diene dimers are taken overhead to a tower whereby these vapors are instantly cooled from 200° — 230° C. to 70° — 80° C. The first distillation tower is operated to recover cyclopentadiene overhead under conditions to provide a minimum contact time for the cyclopentadiene monomer at temperatures $>80^\circ$ — 100° C. Methylcyclopentadiene and heavier materials are fed to a second tower where the methylcyclopentadiene is recovered as the overhead product.

This invention will be better understood by reference to the flow diagram shown in the drawing.

In reference to the attached drawing, stream 1, any thermally stable organic fluid (high boiling hydrocarbon 371+) may be used. This fluid is then super-heated in furnace 2 to approximately 371° C. Leaving the furnace by stream 3, 5, and 6 to tower 4. The use of multiple hot injection points to the tower aids in controlling the desired cracking temperature within the cracking zone. The cracking zone tower 4 may have 10 to 30 plates, depending on the required cyclo or methylcyclopentadiene cracking time. This cracking time may be varied from 1 to 30 seconds, this being a function of the number of plates in tower 4. Laboratory data on vapor phase cracking at 400° — 430° C. show the dimers of cyclo and methylcyclopentadiene are all converted to their respective monomers in 5 seconds contact time. Stream 7 is the thermal stable fluid (oil) being removed from the bottom of tower 4 to be recycled back to the tower after preheating in furnace 2. Stream 8 contains the cracked monomers of cyclo and methylcyclopentadiene, some acyclic diolefins (isoprene, piperylene, and hexadienes), uncracked dimers of acyclic diolefins and some entrained thermally stable oil. The overhead vapor temperature of tower 4 is maintained at 220° — 230° C. (end point of the original dimer feed stream 24). To prevent the entrainment of the thermally stable oil with the vapors (stream 8) it is necessary to introduce the hot oil a few plates below the top of tower 4. Stream 8 has the following composition:

	Weight percent
Cyclopentadiene	35.7
Methylcyclopentadiene	35.1
C_7 cyclodienes	7.2
C_5 and C_6 acyclic dienes	5.3
C_5 and C_6 acyclic dimers	16.7
	100.0

Stream 8 is then fed to tower 9 having 10 to 15 plates. The cracked vapors are instantly quenched to a temperatures of 70° to 80° C. by the liquid reflux of methylcyclopentadiene of the seventh or eighth tray from the top of column 9.

Stream 10 (approximately 37 weight per cent based on feed stream 24) is the cyclopentadiene plus some acyclic C_5 dienes. Part of this stream is condensed by

condenser II and returned as liquid reflux to the tower. A minimum reflux is maintained to insure the separation of the C₅ diene monomers (overhead vapor temperature of 45° C.). Stream 10 should have the following composition:

Component:	Weight per cent
Cyclopentadiene	91.6
C ₅ acyclic dienes	6.9
Methylcyclopentadiene	1.5
	100.0

The major portion of the C₅ acyclic dienes may be stripped from the dimerized monomers, thus giving an increase in cyclopentadiene from 91% to 97%.

Tower 9 bottoms temperature is maintained at 170°-180° C. by removing stream 12 and preheating in heat exchanger 13, returning the liquid to the bottom of the tower. For recovery purposes this heat requirement could best be supplied by an external heating medium so the tower bottoms (methylcyclopentadiene and un-cracked dimers) will have a minimum hold-up time before stream 25 is fed to tower 17 for recovery of the methylcyclopentadiene. Stream 25 has the following composition:

Component:	Weight per cent
Cyclopentadiene	0.5
Methylcyclopentadiene	53.6
Cyclopentadiene dimer	2.0
Methylcyclopentadiene dimer	3.0
C ₅ acyclic dienes	4.0
C ₇ cyclic dienes	11.1
C ₅ and C ₆ acyclic diene dimers	25.8
	100.0

Stream 18 (approximately 33 volume per cent based on feed stream 24) is partially 19, so a minimum reflux may be returned to the top tray to maintain an overhead vapor temperature of 75° C. Composition of stream 18 is as follows:

Component:	Weight per cent
Cyclopentadiene	1
Methylcyclopentadiene	90
C ₆ acyclic dienes	8
C ₇ cyclic dienes	1
	100

Stream 20 is the tower 17 bottoms having the following composition:

Component:	Weight per cent
C ₇ cyclic dienes	26.5
Cyclo and methylcyclo dimer	15.0
C ₅ and C ₆ acyclic diene dimers	58.5
	100.0

Part of this stream is heated by exchanger 21 and returned to the bottom of tower 17 to furnish heat for the distillation (bottoms temperature of 150°-160° C.). Stream 22 may be a means of purging C₇ cyclic dienes and C₅ and C₆ acyclic dimers from the system. Stream 23 is a recycle stream of the above materials returned to the cracking tower 4 since this stream contains some dimerized C₅ and C₆ cyclic dimers formed during the distillation steps.

Feed stream 24 and any recycle streams 23 or 14 are preheated in furnace 15 to a temperature of approximately 177° C. The partially vaporized feed line 16 is fed to the first or second tray from the bottom of the cracking tower 4. Minimum contact time in the furnace 15 is desired, since coking may occur if cracking is allowed to occur in this part of the equipment.

Any entrained cracking oil (streams 1) carried over-

head with stream 8 is removed from the system by purge stream 22.

Presented below are further details of this invention.

The feed stock for the process of this invention as detailed above is a cracked petroleum fraction containing preferably from about 55 to 82 weight per cent of cyclopentadiene and methylcyclopentadiene (as dimers or codimers) boiling in the range of 150°-220° C. with 85% or more boiling in the range of 170°-220° C. Further details on the components and typical actual feed composition are presented directly below:

15	Composition	Range (Wt. Percent)	Typical (Wt. Percent)
Cyclopentadiene ¹	33-47	38.5	
Methyl Cyclopentadiene ¹	22-35	33.7	
C ₇ Cyclo dienes ¹	4-9	6.9	
Acyclic Dienes ¹	4-9	7.3	
Aromatics, Olefins, Paraffins, Dibolefins, Polymers	37-0	13.6	

¹ Present as dimers and codimers.

The oil utilized to countercurrently contact dedimerized monomers is heated to a temperature of 300°-500° C. and is fed to the cracking tower at multiple points such that all zones of the tower are operated at a temperature 350° C. and a sufficient liquid level of oil is carried on each tray. The quantity of hot oil circulated may be varied depending on the concentration of cyclo dienes to be cracked in the dimer feed (circulation rate covering 10 to 100 parts oil to 1 part dimer feed). The oils utilized are thermally stable organic preferably hydrocarbon saturates, i. e., paraffin or naphthenic oils having an initial boiling point of 371° C. atmospheric, so that the oils are in the liquid phase in tower 4.

Aromatic and oxygenated compounds of similar characteristics may also be employed.

An analysis of a typical hydrocarbon oil is as follows:

COMPOSITION OF "BAROSA 56" OIL

ASTM Engler Distillation (10 mm.)	
Vol. per cent:	° C.
IBP	232
5	267
10	277
20	293
30	301

Gravity, API @ 60° F	30.4
Aromatic content	free
Neutralization number	0
Pour point, ° F.	20
Viscosity index	105

The improved method of this invention is illustrated by the following examples.

In obtaining laboratory data the hot oil was fed as a liquid at 350° C. to the top tray of a 15-plate Oldershaw column. Since it was not possible to inject hot oil at various plates, additional heat required to maintain the column at 350° C. was obtained by electrically heating the column. The hot oil circulation rate was ten times the dimer feed rate.

A cyclodiene dimer concentrate containing 38.9 weight per cent cyclopentadiene and 40.1 weight per cent methylcyclopentadiene was fed to a fifteen-plate column

held at approximately 340° C. by circulating hot oil to dimer feed at a ratio of 10/1 respectively. Additional heat required to maintain this temperature was applied electrically since the hot oil was fed as a liquid to the top of the column only. The cracked vapors of cyclo-dienes and uncracked acyclic dimers left the cracking column at temperature of 230° C. and were fed to a distillation column having 20 plates. This tower was operated at 1 to 1 reflux ratio to maintain an overhead temperature of 43° C., a feed plate (fifth from bottom) temperature of 70°-80° C., and a bottoms temperature of 170° C. Analysis of the fractionating tower overhead cyclopentadiene product and the methyl-cyclopentadiene and heavier materials as a bottoms product are as follows:

ANALYSIS¹

Fraction	Cyclopentadiene Yield, Wt. Percent	Methyl-cyclopentadiene Yield, Wt. Percent	Total Wt. Percent
Fractionator Overhead	94.3	2.9	97.2
Fractionator Bottoms	-3.5	63.5	-----

¹ Analysis obtained by ultraviolet procedure after the sample has been dimerized.

The overhead product may be increased in purity by stripping 2 to 3 weight per cent C₅ acyclic dienes from the dimerized fraction. The negative answer obtained for cyclopentadiene on the fractionator bottoms indicates a minimum dimerization was occurring within the tower under conditions employed. Some may be present in the bottoms stream since the ultraviolet procedure is not as accurate when applied to such a mixture high in methyl-cyclopentadiene and other impurities.

It will be further understood that the foregoing examples have been given merely for purposes of illustration, but that other modifications of the present invention are possible without departing from the scope of the appended claims.

What is claimed is:

1. In a process for separating and recovering cyclopentadiene and methyl cyclopentadiene from their dimers and codimers in a cracked petroleum concentrate by vapor phase cracking of the dimers and codimers in said concentrate, the improvement which comprises passing said dimers and codimers in the vapor phase up through the cracking reaction zone in a fractionating column; simultaneously passing countercurrent to said vapors a thermally stable organic oil which boils above

an initial boiling point of 371° C. under atmospheric pressure down through said reaction zone by introducing said oil at an upper part in said column; preheating said thermally stable oil to a temperature in the range of 300° to 500° C. before it is passed into the upper part of the fractionating column; taking off a low boiling vapor fraction containing cyclopentadiene and methyl cyclopentadiene monomers with their dimers and codimers at overhead vapor temperatures of 200° to 230° C. from an upper part of the fractionating column above the point where said thermally stable liquid oil is introduced for further fractionation and recovery of monomers from the overhead product, and withdrawing the thermally stable liquid oil from a bottom part of the fractionating column.

2. In a process for separating and recovering cyclopentadiene and methyl cyclopentadiene monomers from their dimers and codimers in a cracked petroleum concentrate by vapor phase dedimerization, the improvement which comprises passing said concentrate into a bottom part of a fractionating column, passing a thermally stable hydrocarbon oil boiling above 371° C. preheated to 300° to 500° C. into an upper part of said fractionating column so that said oil passes simultaneously countercurrent to vapors of said dimers and codimers in a cracking zone within said fractionating column, withdrawing overhead from said fractionating column cracked monomers of cyclopentadiene and methyl cyclopentadiene with uncracked dimers at a temperature of 220° to 230° C. and withdrawing from a bottom part of said fractionating column the thermally stable hydrocarbon oil.

3. The process as defined in claim 2 wherein said thermally stable hydrocarbon oil is introduced onto plates below top plates in the fractionating column, and wherein in said cracked petroleum concentrate of the dimers and codimers is introduced onto a lower plate above bottom plates in the column.

4. The process as defined in claim 3, wherein the cracked petroleum concentrate is introduced preheated to about 177° C. as a partially vaporized feed and wherein the thermally stable hydrocarbon oil withdrawn from the bottom of the column is heated to 300° to 500° C. and recycled onto plates at an upper part of said column.
